UNITED STATES PATENT OFFICE.

GEORGE KERR ANDERSON, OF MEMPHIS, TENNESSEE.

TACHYGRAPHY AND TYPE-WRITING MACHINE.

SPECIFICATION forming part of Letters Patent No. 440,341, dated November 11, 1890.

Application filed April 20, 1889. Serial No. 307,928. (No model.)

To all whom it may concern:

Be it known that I, GEORGE KERR ANDERSON, a citizen of the United States, residing at Memphis, in the county of Shelby and State 5 of Tennessee, have invented certain new and useful Improvements in Tachygraphy and Type-Writing Machines, of which the following is a specification.

My invention relates to an improved method 10 of writing tachygraphically and to tachygraphic type-writing machines, and has reference more particularly to that class in which the printing characters print in a straight line across the sheet of paper.

15 The present invention is designed as an improvement upon that for which I received Letters Patent of the United States, dated September 10, 1889, No. 410,628.

In the accompanying drawings, Figure 1 is 20 a top plan view of my improved machine with the roll of paper removed; Fig. 2, a side elevation of the same with part of the ribbon-supporting mechanism indicated in dotted lines; Fig. 3, a perspective view of the bed or base 25 plate and the key-board; Fig. 4, a horizontal sectional view on the line $x-x$; Fig. 5, a perspective view looking from the under side of the movable bed or plate to which the printing characters are secured; Fig. 6, a sectional 30 view illustrating the manner in which the key-bars are secured to the base-plate; Fig. 7, a view illustrating the construction and arrangement of the ribbon-supporting mechanism; Fig. 8, a sectional view illustrating the 35 construction of the paper-feed mechanism, and Fig. 9 a sectional view of one of the finger-buttons.

The object of my improvements is to reduce 40 the number of keys on the key-board sufficiently to enable them all to be operated simultaneously by the two hands without shifting the fingers from one key to another.

In the use of my improved machine I employ 45 three groups of characters for the type and keys—one to represent the general phonetic consonant alphabet, one to represent the general phonetic vowel alphabet, and a third to represent a few terminal consonants of very frequent occurrence. The consonants 50 of the first group are combined to form other

consonants and combinations of consonants and the vowels of the second group to form other vowels and combinations of vowels, and in selecting the letters which compose these groups great care has been taken to select 55 those of the most frequent occurrence, so that in actual work they will outnumber the combination-letters greatly. In forming the first consonant group I have endeavored to employ as few characters as possible by which a complete consonant alphabet could be formed, and in forming the vowel group I have also endeavored to employ as few characters as possible with which a vowel alphabet could be formed. In forming the group of terminal 60 consonants I have not sought to represent every terminal consonant, but only a few of the most frequent occurrence. The new features so far disclosed, then, consists in the selection of frequently-occurring letters to form 65 each group and in the use to form these groups of a very small number of characters with which they can be formed.

In order to further reduce the number of characters and strokes of the machine necessary in writing and make the system more complete, I use an arbitrary character, sometimes to show that all the letters in a line are read backward or sometimes to show that the vowel in the line is to be read after certain 70 characters—as, for example, L or after R—instead of before said characters, as printed. By this means I am enabled to print at one stroke many words which would otherwise require two, such as “friend,” “blind,” “time,” 75 &c.

From practical experience I have found that the fourteen characters—viz., S T H K . P A U E L R N T S—are peculiarly applicable for the practical operation of my improved method, and in this case the machine for printing or writing the same need have only fourteen type and keys—one for each character—as in my improved machine, and all of these keys are adapted to be struck 80 simultaneously by the two hands.

The first five letters of the above system—viz., S T H K P—I use singly and in certain combinations to represent an entire phonetic consonant alphabet, the table below giving 85 90 95 100

the different characters and their consonant representations:

5	T H K represents b	S H K represents w
	S T H K represents ch	S T H K represents sw
	K P represents d	S T K P represents wh
	T H P represents f	S T K represents y
	S T K P represents g	S T H K P represents z
	T K represents j	S T H K P represents ing
	T K represents l	T H represents s
	T H K P represents m	H represents t
	S T H K P represents sm	K represents h
	S T H P represents mp	P represents k
10	H K P represents n	S T P represents p
	S T H P represents q	S T H represents st
	T K P represents r	S T K represents sh
	S T P represents tw-dw	S T K represents sk
	T H P represents v	T H P represents sp

The three vowels A, U, and E, taken singly and in combinations, are used to represent the vowels and diphthongs of the alphabet, as indicated in the following table:

20	A represents A	A represents A
	U represents U	U represents U
	E represents E	E represents E
	U E represents I	U E represents I
	A U E represents O	A U represents AU OU OI
	A E represents AE	A E represents AE and initial A, E, or O.

The letters L R N T S, which are terminal consonants that are likely to occur very frequently in writing, have no representation beyond what they themselves are, except that T is sometimes used to represent D and S sometimes represents soft C. By this system I can print a vowel between an initial consonant and any terminal consonant in the last group; but there are many words in which one of the letters R and L comes between the initial consonant and the vowel—such as “friend,” “blind,” &c.—and as there is not room on the key-board for but one more key this additional key (which prints preferably a dot) is employed to indicate that the vowel is read after R or L instead of before these letters as printed.

40 Whenever it is desired to print the letter S the finger-key bearing the representation of said letter will be struck, and the same is true of the letters T, H, K, and P, which, when printed alone, retain their ordinary significance. If, however, it is desired to represent B, it will be necessary to strike the keys T H K, and in like manner the letters D, F, and G are represented, respectively, by the characters K P, H P, and T P. This manner of 45 representing the characters which are not otherwise represented is what I term “combining,” and of course the operator must learn the combinations in the table above given; but as soon as this is accomplished practice 50 only is required in order to enable the operator to print phonographically from dictation.

Only one word or part of a word will be printed on each line, and as soon as an impression is made, though it be but a dot, the 55 paper will be fed forward a distance equal to a line. The characters printed are plain Roman characters, which are easily read and cannot be confounded or confused with one another, and are so selected that in actual 60 work they outnumber combination letters or characters in the proportion of five to one.

Referring now to the drawings, I will describe a machine which I have successfully operated on the foregoing principles.

A indicates a base-board, which may be 70 made of wood or metal and of any desired shape, and B indicates a metallic block, which is secured upon the base-board by screws C passing up through the latter. The block is provided with an upwardly-projecting rim or 75 flange *a*, said flange and block being provided with radial slots *b*, in which the key bars or levers D are mounted, the said block being also provided on its under side with feet *c*, as shown in Figs. 2 and 3.

Formed upon the block or plate B are upright lugs or posts *d*, which serve to support the paper-feed mechanism, and shorter lugs or posts *e*, to which the platen or plate carrying the printing characters is pivoted.

Block or plate B will, for the sake of lightness, be made open at one end and is provided with inwardly-projecting lugs *f*, for a purpose presently explained.

The key bars or levers D are narrow flat 90 pieces of metal perforated at a point near their inner ends to receive a wire yoke or staple *g*, the main arm of which passes through the said key bars or levers and forms the pivot or journal upon which the key bars or 95 levers oscillate or swing.

As shown in Fig. 6, the arms of the yokes or staples *g* extend downward through holes or perforations in the block or base B, and it will also be seen upon reference to said figure 100 and to Figs. 1 and 3 that a single yoke or staple may be arranged so as to form the pivot or journal for two or more key bars or levers. The lower ends of the yokes or staples *g* will 105 advisably be bent or clinched against the lower face of the block, so as to prevent their becoming loose. By providing the block B with the slotted upright flange *a* the key bars or levers will be prevented from moving side- 110 wise or wabbling during their operation. It is obvious that this flange need not necessarily be at the edge of the block B, but may be at most any other point on the block. This construction and arrangement of the lever-mounting devices render unnecessary deep 115 slotting of the block and also enable the staples or yokes to be bent into proper form and applied to the levers or bars before the latter are placed in position.

The levers or bars D are flattened out at 120 their inner ends, as shown in Fig. 3, so as to permit the use of a bar thinner than the face of the type, and therefore light, and are supported at said inner end by a plate or cross-bar *h*, provided on its upper face with a pad 125 or cushion *i*. The cross bar or support *h* is carried by screws *j*, which screw into the lugs *f* of plate or block B, said screws being surrounded each by a coiled spring *k*, as shown in Figs. 3 and 4, so that by screwing the screws 130 into the lugs the springs will be compressed and the bar or support lowered.

Engaging at its ends with the feet *c c* or other part of the block or plate *B* is a rod *l*, which extends across the machine beneath the ends of the bars or levers *D*, as shown in Fig. 4. A coiled spring *m* (one for each key bar or lever) is connected at one end with the rod *l* and at the other end with one of the key bars or levers, thereby holding the latter down upon their support and away from the printed characters.

At their outer ends the key bars or levers are provided with buttons *n*, which are made of a single piece of hard rubber or similar material, the shank of the button being slotted to receive the key bar or lever, to which it is riveted, as indicated in Fig. 9. It is not necessary that the shank be slotted, as the button may be riveted to the side of the key bar or lever, as illustrated in Fig. 2. By making the shank long and integral with the body of the button the liability of the button on one key-bar striking the adjacent bar is avoided, and the use of rivets to connect the shank and body, which renders the button unsightly, is dispensed with.

E indicates the plate which carries the printing characters, the said plate being provided with perforated ears *o* to receive pivot-screws *p p*, by which the plate is secured to the lugs *e e*.

The printing characters, as shown in Fig. 5, are arranged in a straight line directly above the flattened ends of the key-bars and will advisably be formed on a single plate *q*, which is secured rigidly to the under side of the pivoted plate *E*. The printing characters may be made of rubber, steel, type-metal, or any other suitable material, and may be secured to the plate *E* in any manner desired, provided they are so arranged as to have one character directly above each key bar or lever. By having the characters in a straight line it will be seen that any number of the characters may be printed simultaneously or any particular character printed alone.

At the outer end the plate *E* is provided with an arm *w*, which is covered with rubber or felt, and which, resting upon the block *B*, limits the downward movement of the plate and prevents its printing characters from resting upon the key-bars.

In order to hold the plate *E* down into proper position, I employ a spring *F*, which bears at one end upon the plate and at the other end is adjustably secured to an arm *G*, which latter is in turn adjustably secured to an upright post *r* of the block *B*. By loosening the screw *s* the arm *G*, with its spring, may be swung around laterally, so as to remove the spring from the plate and permit the latter to be swung backward to have access to the printing characters for cleaning or other purposes, and it will also be seen that by tightening or loosening the nut *t* the tension or force of the spring may be increased or diminished, as desired.

The arm *G* projects out over one side of

the plate *E* and serves to limit the upward movement of said plate when struck by the key bars or levers, a cushion *u* being secured to the upper side of the plate to reduce the jar and noise.

The roll of paper is carried by an L-shaped arm or support *H*, secured to the base-block *B*, the extreme outer end of the horizontal portion of said arm being bent upward, as shown at *v*, to prevent the accidental displacement of the roll, it being necessary to raise the roll up to slip it off over the bent end *v*.

Pivoted to the outer end of the plate *E* is a pawl or dog *x*, which is adapted to engage with a ratchet-wheel *y*, secured to the shaft *z* of the feed-roll *I*, as shown in Fig. 1, the pawl being held in engagement with the ratchet-wheel *y* by means of a coiled spring *a'*, bearing at opposite ends against or connected with the pawl and the plate *E*.

The rubber feed-roll *I* is made considerably larger than is usual and secured upon a hollow shaft *z*, the shaft being threaded externally at one end to receive nuts *b' b'*, by means of which the ratchet-wheel *y* is secured in position upon the shaft, as shown in Fig. 8.

Projecting into the ends of the hollow shaft *z* are pintles or journals *c' c'*, which have their bearing in the upright posts *d d* of block *B*, the journals being secured to the shaft by means of set-screws *d' d'*, as shown, and provided at their outer ends with flat rubber rollers *e' e'*, as shown in Figs. 1, 2, and 8.

100

J indicates a presser-roll, which is arranged parallel to the feed-roller *I*, the said presser-roll being secured rigidly upon a hollow shaft *K*, into the ends of which project L-shaped arms *L*, which project horizontally from the posts *d d*, as represented in Figs. 1 and 2. Springs *M* encircle the rods or arms *L* and bear at opposite ends against the posts *d* and a lug or shoulder on the arms, the said springs serving to hold or draw the presser-roller *J* against the feed-roller.

110

O indicates the inking-ribbon, which extends transversely across the machine between the printing characters and the key bars or levers, the ribbon being carried at its ends by spools which turn upon shafts *Q Q'*. The shafts are mounted loosely in the upper ends of arms or brackets *R*, secured to the base-plate *A* or to the block *B*, so that either one of the shafts *Q* or *Q'* can be moved longitudinally to bring its particular spool-disk *P* into engagement with one of the rollers *e'*.

115

In order to hold the disk *P* in engagement with the roller *e'*, the brackets *R* are each provided with a flat arm *N*, which bears at its upper end against the pointed ends of shafts *Q Q'*, the arm holding the disk against the roller with sufficient force to cause the latter to rotate the disk, but not to interfere with the rotation of the shaft.

120

The arm *N* is pivoted upon a pin or bolt *S*, which is encircled by a coiled spring *T*, Fig. 7, designed to exert the necessary pressure upon the said arm, so that when one arm is

130

bearing upon its shaft the other arm may be swung laterally upon its pivot out of engagement with its shaft.

U indicates a ribbon-guide, which is made of a single piece of wire bent back upon itself to form an elongated eye through which the ribbon is passed, the length of the eye being regulated by means of a rubber block V, slipped onto the guide and embracing the two arms thereof. The guides are carried by the upright posts d d, Figs. 2, 7, and 8, and are adjustable lengthwise in the posts, the stems of the guides receiving the pressure of coiled springs W, seated in recesses in posts, as represented in Fig. 8. The springs are held in place by means of caps or plates X, secured to the under side of the block B.

The strip of paper is fed beneath the pivoted feed-plate E, passing between the ribbon and the key bars or levers, thence around the lower face of roller I, and up between said roller and the roller J. In order to prevent the unwinding of the paper from the roll from interfering with the operator, an upright rod Y is secured to the block B, which prevents the paper from falling onto the keys.

The operation is as follows: The operator presses down upon one or more of the buttons, and thereby throws the inner flattened end of the key lever or levers struck upward and causes the latter to carry the paper up against the inking-ribbon and the ribbon against the printing characters, thus making an impression on the paper. A further movement or depression of the button raises the inner end of the key-bar still higher and elevates the outer free end of the feed-plate E against the pressure of spring F, the pawl on the latter riding over the teeth of the ratchet-wheel, against which it is urged by the pawl-spring. As the finger is removed from the button, the spring m returns the key bar or lever to its normal position, and the feeding-plate being unsupported also falls; but inasmuch as the plate has to actuate or turn the heavy roller I its descent will be slower than that of the key bars or levers, thereby giving the latter time enough to reach their seat before the plate reaches its seat and pre-

venting a double impression, which would likely occur were the feed-plate permitted to follow with the key-bars. From this construction it will be seen that the feed-roll will be moved or rotated a certain and predetermined distance at each reciprocation or oscillation of the feed-plate, so that after each impression (of one or more characters) the paper will be fed forward the requisite distance.

The holes in the key-bars are made larger than the staple or pivot-wire passing through them, so that the wires may be bent before inserting them in the bars, the larger hole permitting their corners to go through it.

Having thus described my invention, what I claim is—

1. The hereinbefore-described method of phonetically recording syllables and words, consisting in the employment of three sets of characters, the first consisting of five consonants to be used singly and in combinations of two or more to represent all the consonants of a phonetic alphabet, the second consisting of a single group of three vowels to be used singly and in combinations to represent all the vowels of the alphabet, and the third group consisting of certain consonants of frequent occurrence as terminals to be used singly with their ordinary signification, all as set forth.

2. The hereinbefore-described apparatus for phonetically recording syllables and words, having a key-board with three sets of characters, the first consisting of five consonants to be used singly and in combinations of two or more to represent all the consonants of a phonetic alphabet, the second consisting of a single group of the vowels to be used singly and in combinations to represent all the vowels of the alphabet, and the third group consisting of certain consonants of frequent occurrence as terminals to be used singly with their ordinary signification, all as set forth.

In witness whereof I hereunto set my hand in the presence of two witnesses.

GEORGE KERR ANDERSON.

Witnesses:

E. M. AVERY,
L. E. WRIGHT.
